RAILWAY BRAKE BEAM

Edwin G. Busse, Chicago, Ill., assignor to Chicago
Railway Equipment Company, Chicago, Ill., a
corporation of Illinois

Application May 7, 1937, Serial No. 141,204

15 Claims. (Cl. 188—223)

The invention relates to railway rolling stock 5 brake beams of the truss type which include a compression member, a strut at the middle thereof, and a tension member extending over the strut, there being tensioning devices secured to the ends of the tension member and bearing against the ends of the compression member either directly or through thrust blocks seated on the ends of the compression member.

Usually these thrust blocks take the form of 10 brake heads through which the end portions of the tension member pass, with nuts or other devices for anchoring the extremities of the tension member to the brake head. Some brake beam assemblies include a separate thrust block 15 element receiving the thrust from the tension member anchorage device and transmitting this thrust to the compression member, leaving the brake head free of the clamping action of the 20 anchorage device.

It is well known in the art that the tension 25 members of the truss type of brake beam frequently break adjacent to their anchorage. To avoid this breakage it has been proposed to increase the sizes of tension members either 30 throughout their length, or at their end portions only by upsetting the ends. Each of these proposed arrangements involves additional expense and is not as effective as desired.

Other proposed arrangements have been directed to eliminating the application of transverse forces to the tension member of the beam by use of pivotal or yielding elements in the connection between the parts, but the theoretical 35 operation of such arrangements have not been borne out in practice.

The main object of the present invention is to 40 avoid breakage of that portion of the tension member of a truss type brake beam which is adjacent to the anchorage of the tension member to the end of the compression member. This result is to be obtained by structure which is simple, effective, and economical and without requiring a brake head and associated parts which 45 cannot be interchanged with A. A. R. (American Association of Railroads) standard heads.

In the accompanying drawings which illustrate the invention—

Figure 1 is a top view of a truss type brake beam embodying one form of the invention.

Figure 2 is a front view of the same beam.

Figure 3 is a horizontal section through one end of the beam and is taken approximately on the line 3—3 of Figure 2.

Figures 4 to 11 are sections similar to Figure 3

but illustrate, respectively, other modifications of the invention.

The brake beam of Figures 1, 2, and 3 includes a compression member 1 of U cross section, a tension member 2 of solid round bar section, a 5 strut 3 which mounts the brake lever (not shown) in the usual manner, and brake heads 4 each seated at 5 upon an end portion of the compression member. The tension rod extends through each brake head from side to side of the latter 10 and projects outwardly beyond the outer side of the brake head which is provided with an opening large enough to easily clear the tension rod. These major parts of the brake beam are the same as previously constructed, and the brake 15 beam is assembled in the usual manner.

A tensioning device 6 is threaded onto the end portion of the tension rod and is tightened against the outwardly facing bearing 7 on the 20 brake head to thrust the latter against its seat on the compression member and to anchor the end portion of the tension rod to the brake head. Preferably the tensioning device includes an integral extension 8 comprising a sleeve fitting 25 closely around the tension rod for a substantial distance beyond the innermost thread on the latter. Preferably extension 8 does not bear, transversely of its axis, against the head.

Any trussed brake beam device deflects and 30 twists when subjected to the heavy forces applied in the application of the brakes and these forces create movement between the assembled parts notwithstanding their initially tight assembly. The arrangement illustrated will permit the 35 brake head to weave or work on the beam without changing the relation or position between the base of the nut and its seat and without interfering with such flexing of the rod as is necessary to accommodate the relative movement between the parts, but the distribution of bending 40 forces to the rod is spread over a greater length of the rod and the creation of destructive bending strains in the rod tending to shorten its life is minimized.

Figure 4 illustrates a construction in which the 45 compression member 11, tension member 12, and the head 14 are the same as previously described but the tensioning device comprises two separate elements, the nut 16 and the sleeve 18 being 50 formed independently of each other. Sleeve 18 includes a flange 19 resting against the outwardly facing bearing 17 on the brake head and transmitting the thrust of the nut direct to the brake head. After the brake beam is assembled, the 55 nut and sleeve will function as a unit, correspond-

ing to the tension device 6-8 previously described, and possesses similar advantages in bracing the end of the rod. Preferably the portion of the flange 19 bearing on the brake head 5 is given the contour of a spherical segment and when the nut is tightened the thrust of the curved surface against the metal defining the opening in the brake head will cause the sharp corner of the latter to disappear, due to pressure 10 or wear, or both, and give, in effect, a socket bearing adapted to accommodate slight swiveling movement of the sleeve member on the brake head when the forces applied to the beam are so great as to impel such movement.

15 Figure 5 illustrates a modification in which the compression member 21 and the tension member 22 are the same as previously described but the brake head 24 has a tension rod sleeve 25 formed integral with and extending inwardly from its 20 outer wall and serving to reinforce the tension rod in place of the thimbles or sleeves 6-8 of Figure 3, and 18 of Figure 4.

The head does not completely clear the rod, as in the previous forms, and no separate sleeve is 25 used, but the rod is held against bending at the point of its anchorage to the head and the transverse forces transmitted to the rod or spread over a substantial length of the rod, thereby attaining the main object of the invention.

30 Other arrangements for securing the desired results are shown in Figures 6 and 7 in which the rod bracing feature is located exteriorly of the head. In Figure 6, the tension member 27 retains its maximum diameter throughout the width of 35 the head 28 and for a short distance outwardly therefrom, as indicated at 29. The rod bracing sleeve-nut has a relatively heavy section 30 with a cylindrical interior portion fitting closely over rod portion 29 and has an interiorly threaded 40 portion 31 spaced from the head and engaging the threaded portion 32 of the rod.

In Figure 7, the lighter section 33 of the sleeve nut is seated against the bearing 34 on the head and the heavy non-cylindrical part 35 of the 45 sleeve nut is spaced from the head.

In each of Figures 6 and 7, the face of the sleeve nut engaging the brake head has rounded outer corners and may rock on the flat bearing offered by the brake head to facilitate the weaving 50 of the tension member and compression member relative to each other without changing the relation between the tension rod and the sleeve nut irrespective of whether the relative movement is in the plane of the beam, or is vertical or diagonal to the plane of the beam.

55 Figure 8 illustrates a separate nut 37 and sleeve 38 corresponding generally to that shown in Figure 4 but the end portion 39 of the tension rod is shown upset to a larger diameter than the body 60 of the rod. Sleeve 38 extends beyond the threads along the upset portion 39 and distributes the transverse forces over a larger area of the rod than is effected by the usual nut anchorage.

The structure shown in Figure 9 is very similar 65 to that of Figure 3 described above, but the inner face of the nut 41 is rounded, forming a rocker-like bearing on the outer face of the brake head 42 and thus accommodating the weaving action between the compression member 43 and the tension member 44.

70 The structure shown in Figure 10 is similar to that of Figure 4 described above, but the seat 45 on the brake head 46 is given a substantial socket contour before being applied to the compression member 47 and the tension member 48. The

flange 49 on sleeve 50 is provided with a similar ball face to fit against seat 45, thus a more extended ball and socket bearing area is provided than will occur in the structure shown in Figure 4.

5 In all of the above described forms of the invention, the brake head will serve as a thrust block to receive the pressure from the tensioning device and to transmit it to the end of the compression member of the beam.

10 It is to be understood, however, that the essential feature of the invention may be embodied in a structure utilizing a separate thrust block, and an illustrative example of such a combination is shown in Figure 11 in which the thrust 15 block 51 is mounted on the compression member 52 and has a cylindrical periphery on which the brake head 53 may rotate to readily bring the contour of the brake shoe (not shown) flush with the wheel tread. The tensioning device 54 may 20 be formed as in any of the previously described structures and preferably has its thrust block engaging face provided with a spherical or rounded contour to facilitate the rocking or swiveling movements referred to above.

25 Except in Figure 5, clearance is shown between the inner wall of the brake head, or thrust block, and the tension rod of the brake beam but this clearance is not essential to all the aspects of the invention and will be immaterial in many installations.

30 The brake heads shown in Figures 6 and 7 embody no departure whatever from the standard A. A. R. heads in general use. The brake heads shown in Figures 3, 4, 8 and 9, and the 35 brake head and thrust block shown in Figure 11, are modified only to the extent of having the tension rod opening slightly enlarged, and the head shown in Figure 10 has the additional countersunk socket-like seat provided therein, but 40 none of these arrangements require the use of different heads. In other words, the invention may readily be embodied in the millions of brake beams now in use without the expense of replacing the heads now on the beams. Obviously 45 this statement does not apply to the structure shown in Figure 5 in which the head is provided with the integral tension rod embracing sleeve 25.

50 All forms of the invention attain the specific object of preventing substantial bending of the tension member of the beam adjacent its anchor to the compression member of the beam and thereby attain the general object of avoiding breakage of the tension member at this point, which breakage has been a very serious problem 55 in the maintenance of railway rolling stock.

This application is a continuation in part of applicant's earlier application filed March 5, 1936 and bearing Serial No. 67,229.

60 Other modifications of the invention may be made without departing from the novel features clearly described above, and the exclusive use of various structures coming within the scope of the claims is contemplated.

65 What is claimed is:

1. In a truss type brake beam structure, a compression member, a brake head seated thereon, a tension member extending through said head from side to side, a tensioning device on the end of said tension member, one side of said head forming a seat for said tensioning device and the other side of said head clearing said tension member and device, the structure including means extending alongside of a part of said tension member and engaging the same to pre- 75

- vent bending of said tension member where engaged by said device.
2. In a truss type brake beam structure, a compression member, a tension member, a standard A. A. R. constructed brake head seated directly on said compression member, a tensioning device engaging said tension member and bearing against said brake head, the structure including rigid means other than the parts mentioned for resisting bending of said tension member adjacent to where it is engaged by said device.
3. In a truss type brake beam, a compression member, a thrust block thereon, a tension member, and a sleeve device enclosing the end portion of said tension member seated on and extending within said thrust block and movable on said block with said tension member and embracing and reinforcing said tension member for a substantial distance inwardly from the point of seating of said tension member on said thrust block.
4. In a truss type brake beam, a compression member, a brake head thereon having a lateral opening, a sleeve-like device seated against the outer face of said brake head and projecting through and having play in said opening, a tension member extending through said device, said device and tension member including means holding them in unitary assembly with each other.
5. In a truss type brake beam, a compression member, a brake head thereon having a lateral opening, a sleeve-like device seated against the outer face of said brake head and projecting through and having play in said opening, a tension member extending through said device, said device and tension member including means holding them against substantial relative movement transversely of their axis and throughout the length of said device.
6. In a truss type brake beam, a compression member, a thrust block thereon, a tension member, and structure anchoring said tension member on said thrust block and movable on said thrust block with said tension member to accommodate movement of said thrust block relative to said tension member but closely surrounding said tension member to reinforce the same and increase the resistance to bending of said tension member adjacent the point of anchorage.
7. In a truss type brake beam structure, a compression member, a tension member, a standard A. A. R. brake head seated on said compression member and including an outwardly facing bearing, a nut threaded on said tension member and seated against said bearing, the structure including a one-piece annular element engaging the periphery of said tension member adjacent said nut to resist bending of said tension member at or closely adjacent to its threaded portion.
8. In a truss brake beam, a compression member, a thrust block thereon, a tension member, and a unit, comprising nut and sleeve parts rigid with each other with the nut part threaded on said tension member and seated against said thrust block and with the sleeve part extending along and snugly embracing said tension member inwardly of its threaded portion.
9. In a truss type brake beam structure, a compression member, a tension member, a brake head seated on said compression member, a nut threaded onto said tension member and bearing against said brake head, said nut including a sleeve fitting around the unthreaded end portion of said tension member to prevent bending of the same adjacent said nut.
10. In a truss type brake beam, a compression member, a thrust block thereon, a tension member having an end portion extending through said thrust block, a nut threaded onto said tension member, a seat on said thrust block opposing said nut, and a device having a flat annular bearing on said nut and seat and gripped between said nut and said seat and constructed and arranged to resist bending of said end portion of said tension member at the base of the threads on said tension member.
11. In a truss type brake beam structure, a compression member, a brake head seated thereon, a tension member extending through said head from side to side, a tensioning device on the end of said tension member, one side of said head being shaped to seat said tensioning device and to closely surround the adjacent portion of said tensioning device to hold said portion of said tension member adjacent said device against bending.
12. In a truss type brake beam, a compression member, a brake head seated thereon and having an inner side wall and an outer side wall, a tension member extending through said head from wall to wall, and a tensioning device on the end of said tension member, the outer side wall of said head having an outwardly facing bearing for said tensioning device and having an inwardly extending sleeve spaced from the other side wall and disposed to enclose the corresponding portion of said tension member to hold it against bending.
13. In a truss type brake beam structure, a compression member, a brake head seated thereon, a tension member extending through said head from side to side, a tensioning device on the end of said tension member, the outer wall of said head forming a seat for said tensioning device and the inner wall of said head substantially clearing said tension member and device, the structure including means for positively resisting bending of said tension member where engaged by said device.
14. In a truss type brake beam, a compression member, a tension member, a brake head seated on said compression member, and a sleeve device closely surrounding and secured to said tension member and extending therewith through said brake head and including a shoulder bearing against said brake head, the opening in said head for said tension member and sleeve device providing for rocking of the latter on said head.
15. A brake beam structure as specified in claim 13 in which the surface of said tensioning device engaging said brake head is rounded to facilitate the rocking of the tensioning device on the brake head seat therefor.

EDWIN G. BUSSE.
